DIVISIBLE ELECTRIC CONDUCTOR

Original Filed Jan. 18, 1936

UNITED STATES PATENT OFFICE

2,176,233

DIVISIBLE ELECTRIC CONDUCTOR

Hugo H. Wermine, Villa Park, Ill., assignor to
Belden Manufacturing Company, Chicago, Ill.,
a corporation of Illinois

Original application January 18, 1936, Serial No.
59,661. Divided and this application March 25,
1938, Serial No. 197,997

4 Claims. (Cl. 174—113)

This application is a division of my co-pending application Serial No. 59,661, filed January 18, 1936, and a continuation in part of my co-pending application, Serial No. 753,657, filed November 19, 1934.

This invention relates to improvements in electrical conductors and more particularly to duplex conductors of the type typified by so-called lamp cord which is now available on the market in the form of a more or less transversely oval-shaped rubber strip in which the conductors are embedded in predetermined spaced relation to each other. Such lamp cord is available in various colors to suit the requirements of different situations and it is characterized by the absence therefrom of the more or less conventional braided fabric covering. Such fabric coverings or sheaths, as heretofore commonly used, have been more or less necessary for the purpose of binding 10 separate insulated conductors together in a single cable or lamp cord, and such braided or like sheaths have been a frequent source of annoyance because of the tendency of the fabric sheath to fray at the ends of the cord or at intermediate 15 points when the braided fabric is worn.

The present type of rubber-covered lamp cord embodies a pair of conductors, either with or without servings of cotton thread or the like, and a one-piece or unitary coating of rubber or similar insulation material. Such cord may be manufactured very economically and at low cost by the simple operation of extruding suitable rubber compound around properly spaced and guided conductor wires. However, one of the difficulties 20 experienced in employing such rubber covered duplex conductor is that it is very difficult to split or divide a length of the duplex conductor into separate insulation covered wires, for example, at the end of a length of the cable for 25 the purpose of connecting the wires to the terminals of a lamp socket, connector plug or other electrical device. In splitting such conductor it is found that the line of division has a very noticeable tendency to migrate from the desired line of separation toward one or the other of the conductor wires with the resultant baring of portions of the wire which it is preferred to keep 30 covered.

It is the object of the present invention to 35 provide a duplex or multi-wired electrical conductor cable or cord embodying an arrangement whereby separation of the wires with the retention thereon of an adequate covering of insulation material is facilitated.

Other objects and advantages of the invention

will be understood by reference to the following specification and accompanying drawing wherein there are illustrated three specific forms of electric conductor cable embodying the invention, and portions of apparatus for producing the improved cable.

In the drawing:

Figure 1 is a fragmentary illustration in section of an extruding head adapted to produce lamp cord embodying the invention; 10

Figures 2 and 3 are sections on the lines 2—2 and 3—3, respectively of Figure 1.

Figure 4 is a section on the line 4—4 of Figure 1, through the cable produced by the apparatus shown in Figure 1; 15

Figure 5 is a perspective of a length of cable produced by the apparatus shown in Figure 1;

Figure 6 is a section corresponding to Figure 3 but showing a modified arrangement; 20

Figure 7 is a fragmentary perspective of an element of apparatus used in producing the cable form represented in Figure 6;

Figure 8 is a cross section also similar to Figure 3, but showing another arrangement embodying the invention, and 25

Figure 9 is a perspective similar to Figure 7, but showing the form of a portion of the apparatus employed in producing the arrangement illustrated in Figure 8.

Referring now to the drawing, the form of lamp cord illustrated in Figures 4 and 5 embodies a pair of electric wires 10, 10, which are preferably, although not necessarily, of stranded construction so as to be flexible to meet the usual requirements of so-called lamp cord. The wires 35 10, 10, are disposed in substantially parallel but spaced relation and they are enclosed in a jacket or shield 11 of rubber or other suitable insulation material which serves to maintain the conductors in their predetermined spaced parallel relation. 40

The shield or jacket of insulation material is formed integrally about the conductor wires and is provided with a pair of chambers 12, 12, which are spaced transversely of the plane of the wires 10, 10, and disposed approximately midway or equi-distantly spaced from said wires. The chambers 12, 12, extend longitudinally of the cable and serve to guide the splitting of the insulating sheath intermediate the wires 10, 10, as indicated at 13 in Figure 5. The cross sectional 50 size of the chambers 12, 12, may be varied considerably, but it is preferable that they be of such size and shape that the width of the insulation material which must be severed or torn in the plane of the openings or chambers 12, 12, is not 55

materially greater than, and preferably less than, the smallest transverse dimension of the rubber insulation material in any plane extending longitudinally of and through either wire.

- 5 For forming the described cable, the wires 10, 10, are guided through suitably spaced apertures in a tip 14 carried by the tip-supporting element 15 of a rubber or like material extruding head. The cross sectional shape of the rubber jacket is 10 determined by the shape of a die opening 16 in a die piece 17 which is supported by means of a nut or the like indicated at 18 and carried by the main casing 19 of the extruding head. The tip-supporting element 15 is also carried by the main 15 casing or housing 19 through the agency of a sleeve 20 which is suitably locked in place in the housing. As indicated, the tip holder 15 is adjustable forwardly and rearwardly relative to the die 17, in this instance being mounted through 20 the agency of screw-threading 21 in the sleeve 20.

Suitable uncured or unvulcanized plastic rubber or similar composition 11a is forced under pressure through the die opening 16 around the spaced conductors 10, 10, which are guided 25 through said die opening by the tip 14 as clearly indicated in Figure 1 of the drawing. The means for feeding the insulating composition 11a under pressure may be a conventional screw press or other means such as is ordinarily used in extruding 30 machines of the type indicated.

For forming the chambers 12, 12, a pair of pins 22, 22, are mounted in the wire guide or tip 14 and project forwardly therefrom through the die opening 16 and beyond the front end of the die 35 as clearly shown in Figures 1 and 2. The projecting parts 22, 22, of the wire guide may be arranged in various degrees of spaced relationship and in some instances they may even be disposed in contact with each other. It will be apparent 40 that the presence of the projecting pins 22, 22, will result in the formation of the chambers 12, 12, in the insulating material intermediate the wires.

The projecting pins 22, 22, preferably project 45 substantially beyond the outlet end of the die opening 16 as indicated in the drawing, it being found that the production of the cable may then be practiced without maintaining any finely adjusted relationship between the wire guiding tip 50 14 and the inner end of the die 17.

It is noted that within the die opening 16 there is considerable pressure on the insulating composition and that such pressure probably has the effect of more or less compressing the rubber-like 55 insulation material. When the rubber emerges from the die opening 16 it may expand slightly, so that there will be no tendency for the composition to close around the ends of the pins 22, 22. However, the length of the pins may be considerably varied. In fact, they may be short 60 enough to terminate within the die opening, but in that event it is advantageous to feed the insulating composition through the die opening somewhat slower and at a lower pressure.

65 The insulation material covered wires issuing from the extruding head may then be subjected to vulcanization or other treatment for imparting to the composition the permanent but resilient qualities of soft vulcanized rubber. Such vulcanization or treatment may be carried on either by the batch method or by a continuous process.

The chambers formed by the pins 22, 22, may, in some instances, tend to close up so as to appear more like elongated, slightly open slits as indicated in Figure 4, such closing being perhaps due 70

to the tendency of the insulating composition to expand upon issuance from the die. Whether or not the chambers thus formed contain either air or some other fluid has not been ascertained. They may contain air, which may possibly find 5 its way thereinto from the front end of the cable as it issues from the extruding head. However, it appears likely that the chambers contain certain fluids in the form of gases produced as an incident to the vulcanizing step. 10

The extent or degree of opening maintained may be varied and it may be controlled by suitably regulating the pressure under which the insulating material is fed into and through the die, by suitably adjusting the length of the pin or pins 15 which produce the openings, and by regulating or maintaining the consistency of the insulation material as required to secure the desired open condition of the openings. It is preferable that the openings be permitted to, or so shaped that they 20 occupy only a small cross-sectional area. The area of the opening is not of material importance, except in so far as it bears on the cross-sectional size of the finished conductor. In order that the latter may be maintained as small as practicable, 25 it is desirable that the openings be permitted or caused to close up to present the slit-like appearance shown in Figure 4. In this way, the cross-sectional size of the finished conductor is maintained at a minimum while affording a maximum 30 thickness of insulation around each wire.

In Figures 6 and 7, there is illustrated the production of another arrangement of conductor embodying the invention. In this form only one pin designated 22a is carried by the wire guiding tip 35 14. The pin 22a is located intermediate the two wires 10, 10 in the plane thereof and serves to produce only a single opening or chamber in the conductor. Such single opening obviously serves the purpose of a pair of openings or chambers as 40 above explained and provides a stronger bond between the respective halves of the rubber jacket around the respective conductor wires 10, 10. Conductor wire embodying this form of the invention may be somewhat more difficult to separate than the form illustrated in Figures 4 and 45 5, and in some instances such increased strength may be desirable.

In Figures 8 and 9, another arrangement is shown. In this arrangement, a single chamber forming pin 22b is employed, the pin in this instance being somewhat hour-glass in cross section. The cross sectional shape of the pin 22b is such that it embodies an elongated dimension 55 extending transversely of the plane of the wire 10, 10, to form an opening or chamber in the insulation jacket, which opening extends beyond the opposite sides of the pair of wires 10, 10. In this arrangement a weaker bond is provided between the opposite halves of the insulation material around the respective conductors so that 60 separation of the cable into independent insulation covered wires is facilitated. The hour-glass shape of opening is also advantageous in that the central portions of insulating material indicated at 23, 23 on opposite sides of the hour-glass shaped opening may abut each other to thereby 65 present complete closing of the opening portions adjacent the widened ends of the opening. During the process of vulcanization, such abutting portions may be more or less united but the joint so formed is comparatively weak and does not 70 hinder separation of the wires in the manner explained.

It will, of course, be apparent that the forma- 75

tion of chambers as above explained may be practiced in connection with conductor cables of more than two wires so as to permit separation of such wires, for example in a three-wire cable. Also the wires of a multi-wired cable may be located all in a common plane or they may be arranged concentrically about a predetermined axis or any other relationship.

Other changes may be made in the conductor structure, in the method of producing the same and in the apparatus therefor, without departing from the spirit of the invention, the scope of which should be determined by reference to the following claims, the same being construed as broadly as possible consistent with the state of the art.

I claim:

1. Divisible duplex electric conductor comprising a pair of spaced conductor wires and a unitary insulation sheath of resilient material, said insulation sheath being provided with a pair of voids located in a predetermined plane intermediate, extending longitudinally of, and spaced from said wires, said voids serving to reduce the area of insulation sheath in said predetermined plane to facilitate and guide division of the duplex conductor by tearing said sheath in spaced relation to the wires. 5
2. Divisible duplex electric conductor comprising a pair of spaced conductor wires and a unitary insulation sheath of resilient material, said insulation sheath being provided with an internal void located in a predetermined plane 10 intermediate, extending longitudinally of, and spaced from said wires, said void serving to reduce the area of the insulation sheath in said predetermined plane to facilitate and guide division of the duplex conductor by tearing said sheath in spaced relation to the wires. 15
3. Divisible duplex electric conductor comprising a pair of spaced wires and a unitary insulation sheath of resilient material, said sheath being provided with a pair of voids located in a predetermined plane intermediate, extending longitudinally of, and spaced from said wires, said voids being in such spaced relation in said plane as to leave a substantially solid web of said resilient material extending from one of the 20 wires to the other, and said voids serving to reduce the area of the insulation sheath in said predetermined plane to facilitate and guide division of the duplex conductor by tearing said sheath in the plane of said voids. 25
4. Divisible duplex electric conductor comprising a pair of spaced conductor wires and an insulation sheath of resilient material, said insulation sheath being provided with an internal void located in a predetermined plane 30 intermediate, extending longitudinally of, and spaced from said wires, said void serving to reduce the area of the insulation sheath in said predetermined plane to facilitate and guide division of the duplex conductor by tearing said sheath in spaced relation to the wires. 30
